[57] CLAIM

The ornamental design for a dish or the like, substantially as shown and described.

DESCRIPTION

FIG. 1 is a top perspective view of a dish or the like showing my new design;

FIG. 2 is an end elevational view thereof;

FIG. 3 is a side elevational view thereof;

FIG. 4 is a top plan view thereof; and

FIG. 5 is a bottom plan view thereof.

The design is characterized by generally vertical side walls, outwardly diverging end walls, and a peripherally extending horizontally disposed rim which arcuately merges with the walls.

FIG.1

FIG.2
